UNITED STATES PATENT OFFICE.

GUTHRIE ALLSEBROOK, OF LONDON, ENGLAND.

CENTRIFUGAL SEPARATOR.

SPECIFICATION forming part of Letters Patent No. 687,291, dated November 26, 1901.

Application filed March 2, 1901. Serial No. 49,615. (No model.)

To all whom it may concern:

Be it known that I, GUTHRIE ALLSEBROOK, engineer, a subject of the King of Great Britain, residing at 2 Harcourt Buildings, The 5 Temple, London, England, have invented certain new and useful Improvements in Centrifugal Separators, of which the following is a specification.

The improvements relate more especially 10 to centrifugal separators known as "cream-separators."

According to this invention the revolving drum of the separator is made pyramidal and of hexagonal or other polygonal or corrugated 15 form in cross-section and is formed of two members, which I call "shells," one within the other and with a small space between. The upper part of the interior of the inner shell is made to serve as a receptacle into 20 which the milk to be operated on can be poured continuously. Passages are formed at each angle for allowing milk to pass from the lower part of this receptacle to the space between the shells. The cream passes away 25 from the upper part of the space between the shells. At the bottom the space between the shells opens into an outwardly-extending annular space in which all heavy impurities in the milk will be retained. From each angle 30 at the base of the outer shell a pipe for skim-milk to pass away extends upward from the lower part of the space and at the top delivers the skim-milk to a suitable collecting-tray such as ordinarily used.

35 The action of the separators is as follows: The milk being delivered to the space between the shells at each edge—that is, at those points which are farthest from the axis at the level at which the milk-supply takes 40 place—descends along these edges, and as it descends the particles of cream contained in it becoming subjected to a gradually-increasing centrifugal action (by reason of the pyramidal form of the drum) escape sidewise 45 to the central portion of each face which is nearer to the axis of the drum and rise upward along these central portions of the faces. Thus the cream can ascend in continuous streams along the central portions 50 of the faces, while the heavier milk descends in separate paths along the edges. Conse-

quently the larger particles of cream are free to separate quickly, and not being carried down far with the milk are never subjected to the greater force to which the milk becomes subjected as it approaches the extreme radius at the bottom of the drum, and it is only the smaller particles of cream which require this greater centrifugal force to effect their separation which alternately becomes 60 subjected to it. The cream passes away from the top, and the skim-milk rises up from the bottom through the ascending pipes at the edges and is delivered from them through suitable outlets at the top. 65

The separator can be used not only for separating cream from milk, but also generally as a centrifugal separator for separating liquids of different specific gravity.

The drawings annexed show various views 70 of a separator constructed according to my invention.

Figure 1 is a side elevation of the separator with the left-hand half in section, taken through the center lines of two opposite faces. 75 Fig. 2 is a similar elevation with the left-hand half in section, taken through two opposite edges. Fig. 3 is a plan view; Fig. 4, a section on the line *a b*, Fig. 2; Fig. 5, a section on the line *c d*, and Fig. 6 a section on the 80 line *e f*. Figs. 7, 8, and 9 show examples of various ways in which the shape of the drum in cross-section may be varied. Fig. 10 shows, on a smaller scale, how either the inner or outer shell may carry distance-pieces. Fig. 85 11 shows, on a larger scale, the means for holding the ring I.

A is a vertical spindle carrying the inner wall B of the revolving drum, which is shown to be made hexagonal. To the base of this 90 wall is secured a circular trough-shaped flange B', which extends upward all around it, and to the top is secured a hollow receptacle B², into which the liquid to be operated is to be poured continuously as the drum is 95 revolved.

C is the outer hexagonal wall, between which and the inner wall is a narrow space. To its base is secured a circular flange C', the outer edge of which is bent downward and 100 made to fit to the outer side of the trough B' and with it forms a hollow circular recepta-

cle in which all heavy impurities in the milk will be retained. To its top is secured a cap C², having a hole formed through it, up through which passes the upper end of the receptacle 5 B², which is made cylindrical.

D is a nut secured onto the exterior of this upper end and bearing against the top of the cap C² to lock the inner and outer walls together.

10 E is a conical casing surrounding the outer wall C to avoid agitation of the surrounding air when the drum is revolved.

15 B³ represents openings at each angle of the lower part of the receptacle B², by which liquid can pass from the receptacle into the interior of the drum at each edge.

20 F represents tubes extending upwardly along each edge from the base to the top of the drum. The skim-milk rises up these tubes and passes out from them through the short branch tubes F'. A little below these branch tubes the cap C² is formed with an inwardly-projecting ring C³, which is circular on the interior. Into this is screwed a ring H.

25 I is a thin metal ring held between the ring H and a shoulder on the ring C³. The cream as it passes up has to pass between the inner edge of the ring I and the exterior of the receptacle B², which at this point is nearly cylindrical, as shown at Fig. 6, and it then escapes by the outlets J. The passage between the ring I and the receptacle B² is somewhat nearer to the axis than the outlet-tubes F', by which the skim-milk is allowed to escape, so 35 that a larger proportion of the milk treated passes away as skim-milk than as cream.

By using rings I of different inner diameters the proportion of cream to skim-milk delivered can be adjusted as required.

40 The inner faces of the outer shell or the outer faces of the inner may have fixed to them projections K, which act as distance-pieces between the shells. Such projections, as shown in Fig. 10, should incline upward 45 toward but not completely extend to the central line of the face, so as not to obstruct the passage of the cream in its inward and upward path. The distance-pieces also serve as baffle-plates to insure that the liquid contained 50 in the space between the inner and outer shells shall be revolved at the same speed as the drum.

It is not essential that the pyramidal casting should be hexagonal with flat sides, as it 55 might be of other number of flat sides; nor need the sides be flat planes. They might, for example, be made to curve or extend inward, as illustrated in Figs. 7, 8, and 9. With all such forms the separation of the 60 lighter from the heavier portion of any liquid would be effected in precisely the same way as above described.

I have called the shells "pyramidal," as they are of general pyramidal shape. The 65 drawings, strictly speaking, show truncated pyramids.

I claim as my invention—

1. A centrifugal separator, consisting of a pair of similarly-situated pyramidal shells joined together at their base, means for rotating them together around their common axis, means for supplying milk to the space between the shells, and means for discharging the separated cream and skim-milk. 70

2. A centrifugal separator, consisting of a pair of similarly-situated pyramidal shells joined together at their base, means for rotating them together around their common axis, a milk-receptacle inside the inner shell communicating with the space between the shells at the edges thereof, and means for discharging the separated cream and skim-milk. 75

3. A centrifugal separator, consisting of a pair of similarly-situated pyramidal shells joined together at their base, means for rotating them together around their common axis, means for supplying milk to the space between the shells, skim-milk pipes passing up the edges of the outer shell, and cream-discharge pipes at the upper part of the outer 85 shell. 90

4. A centrifugal separator, consisting of a pair of similarly-situated pyramidal shells joined together at their base, means for rotating them together around their common axis, a milk-receptacle inside the inner shell communicating with the space between the shells at the edges thereof, skim-milk pipes passing up the edges of the outer shell, and cream-discharge pipes at the upper part of the outer 95 shell. 100

5. A centrifugal separator, consisting of a pair of similarly-situated pyramidal shells joined together at their base, distance-pieces between them, means for rotating them together around their common axis, means for supplying milk to the space between the shells, and means for discharging the separated cream and skim-milk. 105

6. A centrifugal separator, consisting of a pair of similarly-situated pyramidal shells joined together at their base, distance-pieces between them, means for rotating them together around their common axis, a milk-receptacle inside the inner shell communicating 115 with the space between the shells at the edges thereof, and means for discharging the separated cream and skim-milk. 120

7. A centrifugal separator, consisting of a pair of similarly-situated pyramidal shells joined together at their base, distance-pieces between them, means for rotating them together around their common axis, means for supplying milk to the space between the shells, skim-milk pipes passing up the edges 125 of the outer shell, and cream-discharge pipes at the upper part of the outer shell. 130

8. A centrifugal separator, consisting of a pair of similarly-situated pyramidal shells joined together at their base, distance-pieces between them, means for rotating them together around their common axis, a milk-re-

ceptacle inside the inner shell communicating with the space between the shells at the edges thereof, skim-milk pipes passing up the edges of the outer shell, and cream-discharge pipes at the upper part of the outer shell.

9. A centrifugal separator, consisting of a pair of similarly-situated pyramidal shells, a closed trough outside and below their base, means for rotating them together around their common axis, means for supplying milk to the space between the shells, and means for discharging the separated cream and skim-milk.

10. A centrifugal separator, consisting of a pair of similarly-situated pyramidal shells, a closed trough outside and below their base, means for rotating them together around their common axis, a milk-receptacle inside the inner shell communicating with the space between the shells at the edges thereof, and means for discharging the separated cream and skim-milk.

11. A centrifugal separator, consisting of a pair of similarly-situated pyramidal shells, a closed trough outside and below their base, means for rotating them together around their common axis, means for supplying milk to the space between the shells, skim-milk pipes passing up the edges of the outer shell, and cream-discharge pipes at the upper part of the outer shell.

12. A centrifugal separator, consisting of a pair of similarly-situated pyramidal shells, a closed trough outside and below their base, means for rotating them together around their common axis, a milk-receptacle inside the inner shell communicating with the space between the shells at the edges thereof, skim-milk pipes passing up the edges of the outer shell, and cream-discharge pipes at the upper part of the outer shell.

13. A centrifugal separator, consisting of a pair of similarly-situated pyramidal shells, distance-pieces between them, a closed trough

outside and below their base, means for rotating them together around their common axis, means for supplying milk to the space between the shells, and means for discharging the separated cream and skim-milk.

14. A centrifugal separator, consisting of a pair of similarly-situated pyramidal shells, joined together at their base, means for rotating them together around their common axis, means for supplying milk to the space between the shells, means for discharging the separated cream and skim-milk, and a conical casing inclosing the shells.

15. A centrifugal separator, consisting of a pair of similarly-situated pyramidal shells, a closed trough outside and below their base, means for rotating them together around their common axis, means for supplying milk to the space between the shells, means for discharging the separated cream and skim-milk and a conical casing inclosing the shells.

16. A centrifugal separator, consisting of a pair of similarly-situated pyramidal shells, means for rotating them together around their common axis, means for supplying milk to the space between the shells, means for discharging the separated cream and skim-milk, with the flange, B', at the base of the inner shell, the flange, C', at the base of the outer shell and fitting into the flange, B', and the nut, D, locking the shells together.

17. A centrifugal separator, consisting of a pair of similarly-situated pyramidal shells joined together at their base, means for rotating them together around their common axis, means for supplying milk to the space between the shells, means for discharging the separated cream and skim-milk, and the ring, I, adapted to vary the cream-discharge.
